United States Patent Office

Des. 193,784
Patented Oct. 9, 1962

193,784

PORTABLE CONTROL DEVICE

Charles W. Haeckler, Edgewood, Pa., assignor to Westinghouse Air Brake Company, Wilmerding, Pa., a corporation of Pennsylvania

Filed Nov. 22, 1960, Ser. No. 62,923

Term of patent 14 years

(Cl. D26—13)

Fig. 1.

Fig. 2.

Fig. 3.

FIG. 1 is a front perspective view of a portable control device showing my new design;

FIG. 2 is a right side elevational view thereof; and
FIG. 3 is a rear elevational view thereof.

The essential features of my design are shown in full lines.

I claim:

The ornamental design for a portable control device, as shown and described.
